CHARLES RIZZO, OF BUFFALO, NEW YORK.

LOCK FOR DOORS, &c.

1,210,695.

Specification of Letters Patent.

Patented Jan. 2, 1917.

Application filed February 14, 1916. Serial No. 78,112.

To all whom it may concern:

Be it known that I, CHARLES RIZZO, a citizen of the United States, residing at Buffalo, in the county of Erie and State of New York, have invented new and useful Improvements in Locks for Doors, &c., of which the following is a specification.

This invention relates to door and window locks of the class requiring different movements of the key with a view of rendering it impossible to unlock the same without knowledge of the particular manner of manipulating the key.

The object of my invention is to simplify the construction and reduce the cost of manufacture of such locks.

In the accompanying drawings: Figure 1 is a fragmentary vertical section of a door provided with my improved lock, the front 20 plate of the lock being partly broken away. Fig. 2 is a similar view, looking in the opposite direction, with the rear plate removed. Fig. 3 is a transverse vertical section on line 3—3, Fig. 1. Fig. 4 is a horizontal section 25 on line 4—4, Fig. 2.

Similar characters of reference indicate corresponding parts in the several views.

1 indicates the body of the door, 2 the mortise in which the elements of the lock 30 are confined, 3 the opening for the key, and 4 the usual plate secured to the edge of the door for covering said mortise.

In the example shown in the drawings, the lock is adapted to be manipulated from the 35 outside only.

5 indicates a plate extending practically throughout the length of the mortise 2 and forming the front wall of the lock case or frame. This plate is provided with a key 40 hole 6 having a branch slot 6^a extending laterally from its eye, and arranged substantially at right angles to its main vertical portion, forming a substantially L-shaped key-hole. A locking bolt 7 is arranged horizontally 45 on the rear side of the plate 5 and guided thereon by straps or guides 8, the bolt being adapted to pass through the usual opening in the face plate 4. Intermediate its ends, this bolt is provided in its upper 50 edge with a series of ratchet teeth 9, two being shown in the drawings, while in its lower edge it is provided with a plurality of operating teeth or projections 10, the purpose of which will be presently described.

55 A suitable detent or pawl 11, which may be constructed in the form of a flat spring, as

shown, is fastened to the upper portion of the plate 5 by rivets 12 or other suitable means. The lower portion of this detent is recessed or cut away, to form a tooth or shoulder 13 which is adapted to engage the ratchet teeth 9, and beyond this tooth the detent is provided with a releasing finger 14 projecting downwardly a suitable distance below the teeth 10 of the locking bolt. This 60 65 detent and said ratchet teeth constitute the main locking means of the bolt when projected.

Arranged in rear of the plate 5 and spaced therefrom is an upright rear plate 15 having 70 its lower portion bent forwardly and downwardly and fastened to said plate. These plates form the case or frame structure of the lock. Projecting outwardly from the rear plate 15 and arranged in line with the 75 eye of the key-hole 6, is a stud 16 adapted to enter an opening in the front end of the key 17. Two wards or segmental ribs 18, 19 are arranged on the inner walls of the plates 5 and 14, respectively, concentrically with the 80 eye of the key-hole. As shown in Fig. 1, the radius of the ward 18 is smaller than that of the ward 19. The bit of the key has corresponding clefts or grooves 20, 21, which receive said wards, thereby preventing the 85 lock from being opened except by its own proper key.

A locking catch 22 preferably in the form of a flat strip of spring metal is secured to the upper portion of the plate 5 and extends downwardly a sufficient distance to cover or overlap the horizontal branch 6^a of the key-hole 6. This catch is provided on its inner face with a locking pin 23 which freely passes through an opening 24 in the plate 5 90 95 and is adapted to interlock with an aperture 25 in the locking bolt when the latter has reached its extreme locking or shot position, as shown in Fig. 5, thereby preventing retraction of the bolt unless released by withdrawal of said pin. This catch forms an auxiliary lock for said bolt.

The inner end of the locking bolt is provided with a pin or projection 26 which is arranged to engage a spring 27 suitably fastened at its upper end to the arm 28. This spring is strained when the bolt is fully projected and tends to retract it when released by the catch 23.

When the bolt is projected, the releasing 110 finger of the detent extends into the path of circular movement of the key-bit, so as to be

tripped by it and raise the detent tooth out of engagement with the teeth 9 of the bolt.

When the bolt is in the unlocked or retracted position shown in Fig. 1, the detent tooth 13 bears on the bolt in front of its series of ratchet teeth 9 and the projection 26 of the bolt is located some distance behind the spring 27. When it is desired to lock the door, the key is placed in the key-hole and 10 engaged with the stud 16. It is then turned counter-clockwise, referring to Fig. 1, whereby its bit engages the first of the lower teeth 10 of the locking-bolt, advancing the latter the distance of one tooth. The key is 15 then again rotated to advance the bolt another step by engaging its second tooth 10. If the bolt has more than two of such teeth, this operation is repeated until the key bit has engaged and cleared the last tooth, when 20 the bolt will be fully thrown and the pin 23 of the spring catch will enter the opening 25 of the bolt and lock it in that position, as shown in Figs. 2 and 5. Before the bolt reaches the limit of its outward movement, its pin 26 engages and strains the 25 spring 27.

To unlock the door, the key is inserted as described and turned to bring its bit in register with the lateral branch 6^a of the key-hole. While in this position, the key is 30 pulled outwardly, thereby causing its bit to enter said branch and bear against the spring catch 22 and withdraw its pin from the aperture 25 of the bolt. As soon as the 35 bolt is thus released, the spring 27 shifts the bolt inward until its rearmost ratchet tooth 9 abuts against the tooth 13 of the detent pawl 11, this movement of the bolt being sufficient to shift its locking aperture out of 40 register with the pin of the catch. The bolt is then retracted by completely turning the key clockwise, once for every tooth 10 of the bolt, the latter being shifted inwardly a step every time the key-bit engages one of said 45 teeth, and the bolt being fully withdrawn when the bit clears the last tooth. In this unlocking operation, the key-bit, before engaging the teeth 10 of the bolt, trips the releasing finger 14 of the detent 11, lifting its 50 tooth or shoulder 13 out of engagement with the ratchet teeth 9, and permitting the bolt to be moved inward by the key-bit, as above described.

Owing to the peculiar construction of this lock and the particular manipulation of the 55 key required to release the bolt, an unauthorized person, such as a burglar, would find it exceedingly difficult to unlock the door, even with a proper key. The key-hole visible on the face of the door is of the 60 ordinary form having a simple slot and an eye and gives no suggestion of the concealed and differently-shaped key-hole in the plate 5 with which the visible key-hole co-operates.

In the example shown in the drawings, the 65 locking bolt has three shifting teeth 10, but it may obviously be provided with a greater or less number of teeth and the lock may be modified in other respects within the scope of the appended claim.

If desired, a burglar alarm may be combined with the lock to give warning in case an unauthorized person should by chance or otherwise succeed in releasing the bolt. The alarm shown in the drawings comprises a 75 trigger-block 29 to which is pivoted a trigger 30 adapted to explode a cartridge 31 arranged in an opening in said block and having a suitable spring 32. The trigger is cocked by hand and is automatically pulled 80 by a trip arm 34 carried by the locking bolt and adapted to engage an upright tappet 35 on the heel of the trigger.

As the door has to be cut away to allow the necessary movement of the trigger, a 85 suitable closure 36 in the form of a hinged cover may be attached thereto, as shown.

I claim as my invention:

A lock, comprising a supporting plate 90 having a key-hole provided with a branch-slot, a locking bolt provided with a series of detent teeth and a series of operating teeth, the latter adapted to be engaged by the bit of a key inserted in said hole, a detent pawl engaging said detent teeth and having a releasing member arranged adjacent to said key-hole in position to be engaged by the bit of the key, a catch arranged to interlock with said bolt in the fully-projected position of the bolt, a 100 portion of said catch extending across said branch-slot to be engaged by the key-bit, and automatic means for partly retracting the bolt upon the disengagement of said catch therefrom.

CHARLES RIZZO.
